UNITED STATES PATENT OFFICE.

HARRY COHN, OF BROOKLYN, NEW YORK, ASSIGNOR TO RELIANCE METAL SPINNING & STAMPING CO., INC., OF BROOKLYN, NEW YORK, A CORPORATION OF NEW YORK.

DESIGN FOR A LIGHTING-FIXTURE OVAL PLATE.

56,050.

Specification for Design.

Patented Aug. 10, 1920.

Application filed April 8, 1920. Serial No. 372,356. Term of patent 7 years.

To all whom it may concern:

Be it known that I, HARRY COHN, a citizen of the United States, residing at Brooklyn, in the county of Kings and State of New York, have invented a new, original, and ornamental Design for a Lighting-Fixture Oval Plate, of which the following is a specification, reference being had to

the accompanying drawing, forming part thereof.

The figure is a plan view of a lighting fixture oval plate showing my new design.

I claim:

The ornamental design for a lighting fixture oval plate, as shown.

HARRY COHN.
